AUTOMATIC CUTOFF FOR PAPERBOARD MACHINES

Theodore A. McArn, Downingtown, Pa., assignor to Downingtown Manufacturing Company, Downingtown, Pa., a corporation of Pennsylvania

Application February 18, 1950, Serial No. 144,977

4 Claims. (Cl. 92—67)

1

This invention relates to new and useful improvements in automatic cut-offs for paper making rolls, and more particularly to means for automatically cutting and removing paper board formed on the accumulator rolls of wet board machines.

Prior to the present invention there existed no feasible mechanism for automatically cutting and removing paper board from the accumulator roll of a wet board machine and the paper board had to be cut and removed from the roll manually. This was done by having the operator of the machine stand beside the accumulator roll and, when the paper board had been built up to the desired thickness, draw a knife across the face of the roll. Because of the limitation in the speed which the operator could run the knife across the face of the accumulator roll the peripheral speed of the accumulator roll had to be kept relatively slow. The maximum speed at which the accumulator roll could be run using this method of removal of the paper board was approximately 150 feet per minute.

By the use of the present invention it has been found that the peripheral speed of the accumulator roll may be doubled. Increasing the speed of the accumulator roll cuts down the amount of pulp picked up by the roll in each revolution giving a smoother and better grade of paper board, thus both the output and quality of the paper board produced is increased.

With the foregoing in mind, the principal object of the present invention is to provide a novel automatic cut-off for accumulator rolls of wet board machines which will cut and aid in removing the paper board from said rolls.

Another object of the present invention is to provide a novel automatic cut-off for accumulator rolls of wet board machines which will allow the roll to be run faster, thus increasing the quality and output of the paper board produced by the machine.

Another object of the present invention is to provide a novel automatic cut-off for accumulator rolls of wet board machines wherein a knife blade is provided which may be caused to rotate with the roll when the paper board thereon has been built up to the desired thickness, and will automatically slice across the face of the roll and remove the paper board therefrom.

A further object of the present invention is to provide a novel automatic cut-off of the above-mentioned type which may be easily attached to any type of accumulator roll.

A still further object of the present invention

2

is to provide a novel automatic cut-off for paper making rolls having the advantages and characteristics set forth and which is entirely efficient and effective in operation and use.

5 These and other objects of the present invention and the various features and details of the construction and operation thereof are herein-after fully set forth and described with reference to the accompanying drawings, in which:

10 Fig. 1 is a side elevational view of an accumulator roll having an automatic cut-off made in accordance with the present invention attached thereto;

Fig. 2 is a sectional view taken along the line 15 2—2, Fig. 1;

Figs. 3a and 3b are views taken along the line 3—3, Fig. 1 showing the knife blade and the knife operating mechanism of the present invention;

20 Fig. 4 is a view taken along the line 4—4, Fig. 1 showing the arm supporting the accumulator roll;

Fig. 5 is a view taken along the line 5—5, Fig. 1 showing a portion of the rotatable arms and the 25 latching mechanism therefor;

Fig. 6 is a sectional view taken along the line 6—6, Fig. 1 showing the bracket used to secure the accumulator roll to the framework of the machine;

Fig. 7 is a sectional view taken along the line 30 7—7, Fig. 3a showing the guide for the knife blade;

Fig. 8 is a sectional view taken on the line 8—8, Fig. 3a showing the bracket for supporting the knife blade;

Fig. 9 is a sectional view taken along the line 35 9—9, Fig. 3a showing the method of securing the air cylinder to the knife supporting bar.

Fig. 10 is a sectional view taken along the line 40 10—10, Fig. 3b showing the limit switch for controlling the direction of operation of the knife blade;

Fig. 11 is a schematic wiring and air diagram controlling the operation of the automatic cut-off mechanism; and

Fig. 12 is a schematic diagram of a wet board machine.

The automatic cut-off of the present invention comprises essentially a knife blade which may be caused to rotate with the accumulator roll of a wet board machine for a portion of a revolution when the paper board on the accumulator roll has been built up to the desired thickness and during rotation therewith be caused to slice across the face of the accumulator roll thus cut-

ting the paper board formed on the roll and aiding in the removal of the paper board therefrom.

Referring more specifically to the drawings, and particularly Figs. 1, 2 and 4, reference numeral 10 designates generally an accumulator roll fixed on a shaft 11 which is supported in bearings 12 carried by arms 13 at opposite sides of the roll 10. The arms 13 are pivotally mounted to brackets 14 by means of pins 15 as shown in Fig. 4. The brackets 14 are carried on ways 16 which are a part of the framework 17. The brackets 14 are each secured to a threaded shaft 18 and may be raised or lowered on the ways 16 by rotating the hand wheels 19. When the brackets 14 are in the proper position on the ways 16, they may be locked thereby securing the cover plates 20 tightly against the rear edge of the ways 16 by means of bolts 21. The position of the arms 13 is adjustable so that accumulator rolls 10 of different diameters may be carried by the same framework 17.

The accumulator roll 10 is positioned so that its center is directly above the center of the supporting roll 22. The paper pulp is placed on the accumulator roll 10 by means of an endless felt 23 as shown in Fig. 12, which travels over a roll 24 partially submerged in a tank of paper pulp 25. The roll 24 picks up a thin layer of paper pulp from the tank 25 and transfers it to the felt 23. The felt 23 in turn transfers the layer of pulp to the accumulator roll 10.

A bracket 26 is secured to each of the arms 13 by means of bolts 26a and carries a microswitch 27 thereon. The microswitch 27 is operated by an arm 28 which is pivotally mounted to the microswitch 27 and is positioned so that it contacts the framework 17. As the paper is built up on the accumulator roll 10, the center of the roll is raised and pivoted about the pins 15 by an amount equal to the thickness of the paper on the accumulator roll 10. As the accumulator roll 10 is raised, the bracket 26 is moved outwardly away from the framework 17 and thus the arm 28 is allowed to be pivoted about the microswitch 27. When the paper board has been built up to the desired thickness the knife, more fully described hereinafter, is actuated by means of the microswitch 27 and slices across the face of the accumulator roll 10, thus cutting the paper board formed thereon and allowing the same to be removed therefrom.

When the paper board is removed from the accumulator roll 10, the roll will fall an amount equal to the thickness of the paper removed therefrom and contact the supporting roll 22. To prevent the accumulator roll 10 from dropping rapidly onto the supporting roll 22, shock absorbers 29 are secured to the brackets 26 and adjusted so that they contact the framework 17. The shock absorbers 29 will cause the accumulator roll 10 to drop slowly into contact with the supporting roll 22.

A pair of arms 30 are carried by the bearing mount 12 along with the shaft 11 upon which the accumulator roll 10 is supported. As shown in Fig. 2, the arms 30 are pivotally mounted adjacent their mid-points on hubs 31 secured to the bearing mount by means of bolts 32. The arms 30 and the accumulator roll 10 may both be rotated with respect to each other and to the bearing mount and they are interconnected by means of a cross frame 33 which is slidably mounted on each of the arms 30 and carries the cutting knife 34 thereon. The arms 30 are also connected at the other end thereof by a channel member 35

secured to each of the arms 30 by means of bolts 36. A cam 37 is securely fastened to each end of the shaft 11 and is adapted to be rotated with the accumulator roll 10. The arms 30 are normally in the position shown in Fig. 1 by the over-balancing of the knife-supporting end of the arms 30, and are held there by adjustable stops 38 carried by brackets 39 which are secured to the supporting arms 13 by bolts 40.

The arms 30 each carry a plunger 41 which is normally held in a retracted position by means of a spring 42. The plunger 41 is operated by a solenoid 43 controlled by the microswitch 27. When the microswitch 27 is closed due to the desired thickness of paper being built up on the accumulator roll 10, the solenoid 43 forces the plunger 41 against the periphery of the cam 37. As the cam 37 is rotated, the plunger 41 is contacted by the shoulder 44 on the cam 37 and the arms 30 are caused to rotate with the accumulator roll 10. The cam shoulder 44 is so positioned with respect to the accumulator roll 10 that as the plunger 41 is contacted by the shoulder 44, a slot 45 extending transversely across the face of the accumulator roll 10 is positioned adjacent to the knife blade 34 and as the knife blade 34 is caused to slice across the face of the roll 10, it enters the slot 45. The slot 45 has a soft metal liner 46 therein as shown which will prevent the knife 34 from becoming nicked, if it should happen to contact the edges of the slot 45.

As the arms 30 reach the broken line position as shown in Fig. 1, a roller 47 secured to the plunger 41 is contacted by a cam 48 secured to the bracket 14 and the plunger 41 is withdrawn from contact with the cam 37. An extension 49 on the arms 30 is contacted by an adjustable stop 50 also secured to the bracket 14 and prevents the arms 30 from any further rotation. After the plungers 41 are withdrawn from contact with the cams 37, the arms 30 are returned by gravity to their original position as shown in Fig. 1.

The cross frame 33 is adjustable with respect to the arms 30 by means of a threaded shaft 51 so that the knife 34 may be properly positioned with respect to accumulator rolls of different diameters. A plurality of connecting links 52 are pivotally mounted to the cross frame 33 by means of pins 53 and also pivotally mounted to the knife 34 by pins 54. Thus the knife 34 may be moved back and forth longitudinally with respect to the accumulator roll 10 and during such movement will cut the paper formed on the roll 10. A plurality of guides 55 are carried by the cross frame 33 and hold the knife blade 34 rigidly from any vertical displacement.

A double-acting air cylinder 56 is secured to the cross frame 33 and has the end of its piston rod 57 fastened to the knife blade 34 by means of a connecting link 58. As air is forced into the cylinder 56, the knife blade 34 is moved across the face of the accumulator roll 10. The knife blade 34 carries a U-shaped stop 59 which actuates a limit switch 60 controlling the flow of air to the double-acting air cylinder 56 and thus the movement of the knife blade 34. When the knife blade 34 is in its extreme right-hand position, as shown in Figs. 3a and 3b, the limit switch 60 is positioned so that air may enter only the right-hand portion of the air cylinder 56 thus forcing the knife blade to its extreme left-hand position and when the knife blade 34 is in its left-hand position, the limit switch 60 is operable to permit air to be admitted only to the left-hand

side of the air cylinder 56 and thus force the knife blade to its extreme right-hand position.

The arms 30 carry a guide member 61 which operates a limit switch 62 secured to the bracket 39. The limit switch 62 is so adapted that it is only in the closed circuit position when the arms 30 are rotating with the accumulator roll 10, and the solenoid operated air valve (more fully described hereinafter) may not be actuated unless the limit switch 62 is in the closed circuit position. This is a safety measure which prevents accidental or continuous operation of the knife 34.

Fig. 11 shows a schematic wiring and air diagram for controlling the operation of the automatic cut-off mechanism. When the microswitch 27 is operated by having the desired thickness of paper built up on the accumulator roll 10, the circuit to the solenoids 43 is closed forcing the plungers 41 into contact with the cams 37. When the plunger 41 is contacted by the shoulder 44 of the cam 37, the arms 30 are caused to rotate with the accumulator roll 10. In this position the knife blade 34 is directly opposite the groove 45 in the accumulator roll 10. As the arms 30 start to rotate, the limit switch 62 is closed, which, in turn, closes the circuit to one of the solenoids 63 or 64 depending upon the position of the other limit switch 60. The solenoids 63 and 64 control air valves 65 and 66 respectively, which admit air to the left and right-hand side, respectively, of the air cylinder 56. When the knife blade 34 is in the right-hand position, and the microswitch 27 and limit switch 62 are closed, solenoid 64 will be energized opening valve 65 and closing valve 66. Thus air will be admitted to the right-hand side of the air cylinder 56 and exhausted from the left-hand side thereof, forcing the knife to the left across the face of the accumulator roll 10. Similarly, when the knife blade 34 is in its left-hand position, solenoid 63 will be energized and air will be admitted to the left-hand side of the cylinder 56 and the knife blade 34 will be forced to the right across the face of the accumulator roll 10. The knife blade 34 is prevented from operating continuously by having the guide 61 come out of contact with the limit switch 62 when the arms 30 are in their upper position thus opening the switch 62, and when the arms 30 drop to their original position, the microswitch 27 will be opened. Thus the circuit to the solenoids 63 or 64 will only be closed during one direction of operation of the knife blade 34.

From the foregoing it is apparent that the present invention provides a novel automatic cut-off which cuts and aids in the removal of paper board from the accumulator roll of a wet board machine. Furthermore, the present invention provides a novel automatic cut-off of the above mentioned type which is of relatively simplified construction, is fool-proof in operation and may be easily adapted to any type of accumulator roll.

While certain embodiments of the present invention have been illustrated and described herein, it is not intended to limit the invention to such disclosures, and changes and modifications may be incorporated and embodied therein within the scope of the following claims.

I claim:

1. In an automatic cut-off for the accumulator roll of a wet board machine, a shaft rotatably mounted to support the accumulator roll, a pair of arms mounted intermediate their ends adjacent opposite ends of the roll for pivotal move-

ment about the axis of said roll, cam means secured to the shaft and rotatable therewith, a plunger secured to each of said arms and actuatable simultaneously into engagement with said cam means to cause rotation of the arms with the roll, electric means operable in response to a predetermined thickness of the board on the roll to actuate the plunger into engagement with said cam means, a knife blade carried by the arms mounted to traverse the face of the roll in either direction and sever the board thereon during such traverse, blade actuating means operable to actuate the blade alternately in opposite directions across the face of the roll, control mechanism comprising a normally open switch and means to close said switch only during rotation of the arms with the roll to actuate said blade actuating means, and second switch means mounted adjacent the knife blade and actuatable by the knife blade to control the direction of traverse of the knife blade.

2. In an automatic cut-off for the accumulator roll of a wet board machine, a shaft rotatably mounted for supporting the accumulator roll, a pair of arms mounted intermediate their ends adjacent opposite ends of the roll, cam means secured to the shaft and rotatable therewith, a plunger secured to each of said arms and actuatable simultaneously into engagement with said cam means to cause rotation of the arms with the roll, electric means operable in response to a predetermined thickness of the board on the roll to actuate the plunger into engagement with said cam means, a knife blade carried by the arms mounted to traverse the face of the roll in either direction and sever the board thereon during such traverse, blade actuating means operable to actuate the blade alternately in opposite directions across the face of the roll, control mechanism comprising a normally open switch and means to close said switch only during rotation of the arms with the roll to actuate said blade actuating means, second switch means mounted adjacent the knife blade and actuatable by the knife blade to control the direction of traverse of the knife blade, and a fixed element engageable by the plunger after a predetermined extent of rotation of the arms operable to disengage said plunger from the cam means and stop rotation of the arms.

3. In an automatic cut-off for the accumulator roll of a wet board machine, a pair of arms mounted adjacent opposite ends of the roll for pivotal movement about the axis of said roll, latch means operable in response to the thickness of the board on said roll to cause simultaneous rotation of said arms with the roll when the board thereon attains a predetermined thickness, a knife blade carried by the arms mounted to traverse the face of the roll in either direction and sever the board thereon during such traverse, blade actuating means operable to actuate the blade alternately in opposite directions across the face of the roll, control mechanism comprising a normally open switch and means to close said switch only during rotation of the arms with the roll to actuate said blade actuating means, and second switch means actuatable by the knife blade to control the direction of traverse of the knife blade.

4. In an automatic cut-off for the accumulator roll of a wet board machine, a pair of arms mounted adjacent opposite ends of the roll for pivotal movement about the axis of said roll, latch means operable in response to the thick-

ness of the board on said roll to cause simultaneous rotation of said arms with the roll when the board thereon attains a predetermined thickness, a knife blade carried by the arms mounted to traverse the face of the roll in either direction and sever the board thereon during such traverse, blade actuating means operable to actuate the blade alternately in opposite directions across the face of the roll, control mechanism comprising a normally open switch and means to close said switch only during rotation of the arms with the roll to actuate said blade actuating means, second switch means actuatable by the knife blade to control the direction of traverse of the knife blade, and means to dis- 15

engage the latch means and stop rotation of the arms when the latter have rotated a predetermined distance.
